UNITED STATES PATENT OFFICE

112,450

DESIGN FOR A SEAT COVER OR THE LIKE

Julius Kletsky, Springfield, Mass.

Application October 12, 1938, Serial No. 80,416

Term of patent 3½ years

To all whom it may concern:

Be it known that I, Julius Kletsky, a citizen of the United States, residing at Springfield, in the county of Hampden and State of Massachusetts, have invented a new, original, and ornamental Design for a Seat Cover or the like, of which the following is a specification, reference being had to the accompanying drawing, forming part thereof.

The figure is a perspective view of a seat cover, showing my new design.

I claim:

The ornamental design for a seat cover or the like, as shown.

JULIUS KLETSKY,
